CLAIM

The ornamental design for a kite, as shown and described.

DESCRIPTION

FIG. 1 is a perspective view of the kite showing our new design;

FIG. 2 is a bottom plan view thereof;

FIG. 3 is a top plan view thereof;

FIG. 4 is a side elevation view thereof, the opposite side being identical in appearance; and,

FIG. 5 is a front view thereof, with the rear view thereof being identical in appearance.

The broken lines shown in FIG. 1 are for illustrative purposes only and form no part of the claimed design.
